UNITED STATES PATENT OFFICE.

HERBERT C. STOCKWELL, OF LOS ANGELES, CALIFORNIA.

MECHANICAL THEATER CENSOR.

Application filed September 19, 1921. Serial No. 501,721.

This invention is broadly new, basic and pioneer with respect to the purpose, method and means to which it appertains, and its object is to obtain a consensus of opinion of theater patrons as to the character of the performances of such theater, and it includes a housing provided with individual counters, and individual push buttons accessible to the patrons as they pass out of the theater, and adapted to be operated by the patrons as they pass; and said counters and push buttons are provided with marks indicating commendation and disapproval so that by operating the appropriate counter the patron can register his opinion of the performance.

Preferably the device is provided with three counters, one marked "Good", another "Medium" and the third "Poor" or with like terms of commendation and disapproval.

In carrying out the invention I have provided the housing with a transparent window and with one or more lights inside said window and have so placed the illumination inside the housing as to attract the attention of the passing patrons; and I also provide the device with an inscription inviting the patrons to push a button, and thus to express their degree of approval or disapproval.

An object is to improve the character of motion picture vaudeville and theatrical performances so that the proprietor or manager of the theater may be guided in his selection of films and plays.

An object is to provide a simple and convenient arrangement for concealment, operation and inspection of the counters.

The invention is not limited as to the performance to be censored. Objects are cheapness and attractive appearance.

Other objects, advantages and features of invention may appear from the accompanying drawing, the subjoined detail description and the appended claims.

The accompanying drawing illustrates the invention in one of its forms.

Figure 1 is a front perspective view of a mechanical theater censor constructed in accordance with this invention.

Fig. 2 is a perspective front view with the door open.

Fig. 3 is a cross-section on line indicated at x^3 , Figs. 1 and 2.

Fig. 4 is a fragmental view of an element assembly that is produced by closing the door of the housing.

Fig. 5 is a view from the inside of the housing, showing elements in assembled position brought about by closing the door.

The housing comprises a box 1 closed on five sides and open in front, and a door or closure 2 which is shown hinged at 3, at its lower edge, to the lower margin of the box and adapted to close the box and to be fastened shut by suitable fastening means 4.

The housing is shown provided with three operative means, as handles in the form of spring returned push buttons 5, 6, 7, carried by and extending through the closure. Adjacent to said push buttons are the inscriptions, respectively, 8, 9, 10 indicating "Good", "Medium", and "Poor", arranged on a window a in the door.

Inside the housing there are provided means as the lamps 11 to illuminate the window and the inscriptions when the appropriate push button is pushed, and inside the housing there are provided counters 12, 13 and 14 adapted respectively to be operated by the appropriate push buttons.

Said counters are rigidly mounted with respect to the box portion 1 of the housing; and actuators in the form of pawls 15, operable by the push buttons appropriate thereto, are arranged to operate the respective counters.

The counters may be fixed to the housing in any desirable way and are shown as supported by attaching means 16 which hold the counters with their faces presented toward the open side of the box so that when the closure 2 is opened, the faces of the counters can be seen.

The pawls for operating the counters are slidably mounted respectively in supports 17 which are secured to the box and hold the pawls in position to be actuated by the actuating means, as the push button handles, when the closure is closed.

An announcer as the bell 18 is arranged to be operated by the handles so that each operation of a counter will be announced, thus to satisfy the patron operating the handle, and also making any double voting apparent to the inspector and to the public. The result of the vote is continuously carried by the numbers on the counters and this can be noted at any time by opening the closure. Suitable fastening means are provided as at 19 for attaching the housing to a support 20.

The announcer is operated through a suitable connection operable by the handles 5, 6, 7 when the door is closed and the handle moved to actuate a counter.

- 5 Such connection is shown in the form of a bail 21 pivoted by pivots 22 to the closure 2, and provided with a member 23 to operate the bell 18. The stem 24 of the operating handle extends through the bushing *b* that 10 is secured in the opening *c* in the closure and terminates in a tappet 25 that abuts the end of, and is adapted to actuate the counter actuator 15, and is also adapted to operate the sounder, when the push button is pushed. 15 Said tappet 25 may be a detachable cap on the stem and forms a stop on the inside of the closure to prevent the handle from being accidentally withdrawn from the closure. 20 The resilient means 26 carried by the door, yieldingly holds the handle in initial position; and the resilient means 27 yieldingly holds the actuator 15 in its initial or retracted position. 25 The member 23 operates the pivoted crotch 28 of the bell hammer 29 which is yieldingly held in initial position by spring 30, operating to hold the crotch against stop 31. 30 In practice the device will be so placed as to attract the attention of the patrons of the theater as they come from the theater. When the patrons respond to the invitation to register their opinions of the play, this is 35 done by each pushing the appropriate push button.
- The support of the push buttons may be arranged in any desired way and may be so arranged as to expose the numbers on the 40 counters at the time the push button is operated; but it is deemed preferable to exclude the public from the knowledge of how the voting is proceeding; and the window *a* of the closure is preferably merely translucent rather than transparent, and is shown as made of ground glass so as to diffuse the light which illuminates the same. Only one light or a plurality of lamps may be employed as shown at 11. 45 In practice the housing will be applied to any suitable support at a place that is in prominent view to the persons leaving the theater. The inscription announcing the purpose of the device is thus brought to the 50 attention of the departing patrons who may

respectively push any one of the buttons, as he desires, thus to register an opinion of the play. Each patron will naturally be deterred from registering more than once, by reason of the likelihood of being detected in any repeating, and also by reason of the public interest toward a fair expression of opinion.

I claim.

1. A theater censor comprising a box having a hinged cover; counters inside and fixed to said box; supports secured to said box; pawls slidably mounted in said supports and adapted to operate the counters; and push buttons slidably mounted in said cover and adapted to operate the pawls and accessible to the patrons of the theater. 65

2. In combination, a box; a closure hinged to said box and provided with an opening therethrough; a bushing in said opening; a handle outside said closure provided with a stem extending through said bushing; a stop on the inner end of said stem to retain the stem in the bushing; said stem being adapted to move to and fro through said bushing; a counter stationed in the box; an actuator for said counter arranged in the box in position to be actuated by the stem when the handle is actuated; and a spring to return the actuator to initial position when the handle is released. 70

3. A theater censor comprising a box; a counter in said box; a closure hinged to said box; an actuator adapted to operate the counter and mounted in said box; and a push button slidably mounted in said closure and adapted to operate said actuator, the said push button having end engagement with the counter when the closure is closed. 80

4. A theater censor comprising a box having a hinged cover; a counter operable within and fixed to said box; an actuator for said counter arranged in said box; a push button mounted in said cover; spring actuated means for normally holding the said actuator in position to actuate said counter; spring actuated means for holding the push button outwardly of said cover and the said push button and actuator being adapted for engagement when the said cover is in closed position. 85

In testimony whereof, I have hereunto set my hand at Los Angeles, California, this 10th day of September, 1921.

HERBERT C. STOCKWELL.
